UNITED STATES PATENT OFFICE.

HARRY GIBNEY CRAFT, OF CLARKSDALE, MISSISSIPPI.

DIRECTION-SIGNAL FOR AUTOMOBILES.

1,281,524.

Specification of Letters Patent. Patented Oct. 15, 1918.

Application filed May 2, 1917. Serial No. 165,987.

To all whom it may concern:

Be it known that HARRY G. CRAFT, a citizen of the United States, residing at Clarksdale, in the county of Coahoma and State of Mississippi, has invented certain new and useful Improvements in Direction-Signals for Automobiles, of which the following is a specification, reference being had to the accompanying drawings.

10 This invention relates to automobiles, and particularly to direction signals therefor.

The general object of the invention is to provide a very simple, easily operated and effective signaling device, whereby the 15 driver of the machine may indicate to approaching machines that he is about to turn either to the right or to the left.

A further object of the invention is to provide a construction of this character in 20 which signal or semaphore arms are pivotally mounted upon the side wall of the car and adapted to be turned from a vertical and housed position to a horizontal and display position, by means of actuating devices controlled by the driver.

25 A further object of the invention is to provide a housing for each semaphore arm so constructed that the semaphore is protected from rain or snow and also providing an inconspicuous support for the semaphore in its 30 inoperative position.

35 A further object is to provide an improved form of semaphore arm in which the electric wires leading to the electric bulb within the head of the semaphore arm are protected from rain and snow and in this connection to provide improved means for latching the 40 semaphore arm in its lowered position and for coincidentally breaking the circuit through the electric light bulb.

45 Other objects will appear in the course of the following description.

My invention is illustrated in the accompanying drawings, in which:—

45 Figure 1 is a perspective view of a portion of an automobile showing my swinging device mounted thereon;

Fig. 2 is a cross sectional view through the 50 arm 13 and the adjacent portion of the housing;

Fig. 3 is a transverse section through the head section and adjacent portion of the housing.

Referring to the drawings, and particularly to Fig. 1, it will be seen that I provide a vertically disposed housing, design-

nated, generally 10, and mounted in any suitable manner upon the side wall A of the car, and extending downward to the running board B of the car. This housing may be 60 conveniently made of sheet metal riveted to the wall of the car at a plurality of points, so as to make the housing thoroughly strong. The housing is closed at its lower end and at its upper end. The interior of the housing 65 is to be lined with a sheet of rubber, or other like cushioning fabric, designated 11, and the side edges of the housing are also to be covered with rubber 12.

Pivotedly mounted within the upper end 70 of the housing is a hollow arm 13, which is T-shaped in cross section, the pivot pin 14 of this arm being disposed outward of the rear end of the arm. The rear end of the arm is pivotally connected to a rod 15, which extends downward at the rear of the housing and through the lower end thereof and through the footboard B. At the outer end of the arm 13, there is formed a casing or head 16, which is approximately triangular 80 in cross section and which extends above and below the plane of the arm 13, so as to provide a relatively wide and relatively long signal target having oppositely disposed downwardly convergent side walls 17. 85 These side walls are preferably painted red, or any other appropriate color, which will attract attention, and the side walls are formed with openings wherein are disposed lenses 18, these lenses being preferably of 90 red glass. Disposed within the housing or target 16 is a lamp 19, preferably an incandescent electric lamp. The wires 20 from this lamp lead out through the inner end of the housing or target 16 and are preferably disposed beneath the upper flange of the T-shaped arm 13. These wires lead to any suitable source of electrical energy. The lower margins of both of the side walls 17 are formed with openings 21 for a purpose 100 to be later stated.

For the purpose of operating each semaphore, I provide a bell crank lever 22, which is pivotally mounted upon the frame of the machine below the footboard B, one arm of 105 this bell crank lever being operatively connected to the rod 15, while the other arm is pivotally connected to a rod 15^a, extending transversely beneath the floor of the automobile and the inclined footboard C to a 110 position adjacent the clutch pedals. There this rod 15^a is connected to a bell crank lever

23 and operatively engaging with one arm of this bell crank lever is a pedal 24 normally held up by a spring, if desired. It will be obvious that when the pedal 24 is depressed, 5 it will rock the bell crank levers 23 and 22, pull down upon the rod 15 and swing the semaphore arm to a horizontal position where it will be plainly evident to machines advancing in either direction. When the 10 pressure on the pedal 24 is released, the arm 13 will swing downward by gravity. It will be noted that the housing 10 has inwardly convergent side walls and that the lower ends of these side walls are outwardly extended to a depth equal to the width of the 15 walls 17 of the target or lamp housing and thus when the arm 13 swings downward, the outer wall of this target or lamp housing and the outer flange of the T-shaped arm 13 will 20 fit closely into the housing 10, so as to form a front wall thereto. The rubber lining or other cushioning material disposed within the housing 10 will cushion the jar incident to the movement of the semaphore into the 25 housing. Furthermore the front wall of the target 16 projects laterally beyond the side walls thereof, as at 25, and this front wall and the outer flange of the T-shaped arm 13 contact with the side edges of the housing 30 10. It will be seen that thus the semaphore is fully protected when in its inoperative position, that rain cannot gain access to the interior of the housing, and that the semaphore is rendered inconspicuous and indeed 35 more or less ornamental to the car itself.

For the purpose of holding the semaphore in its lowered position and in close engagement with the housing 10, I mount on the rear wall of the housing, adjacent its lower 40 end, the spring clamp or locking device which comprises a base 26 and two divergent spring actuated arms 27 having detent ends. These detent ends are adapted to engage in the openings 21 formed in the side walls 17 45 of the target and hold the semaphore in its lowered position against accidental jarring. Of course, a positive movement of the semaphore toward its display position will detach the spring actuated arms from their engagement with the semaphore.

50 Preferably one of the clamping members 27 is also used to break the circuit through the signal light 19 when the arm is in its lowered position. This may be accomplished in a variety of ways. I have illustrated, however, in Fig. 3, a contact member 55 29 which is carried upon one of the clamping members 27 and which is connected in circuit with the source of energy and the lamp 19. Mounted in position upon the base 26 is a contact member 30 from which a wire leads directly to the lamp. The contact member 29 may be insulated from the corresponding clamping member 27 in any suitable manner and I have shown for this pur-

pose the clamping members as being made of insulating material. Now when the members 27 are forced apart by the walls 17 of the target or lamp housing, the contact 29 will be electrically disengaged from the contact 30 and break the circuit through the lamp. When, however, the lamp housing or target is withdrawn from between the members 27, they will be caused to close by the springs 31 and the contacts 29 and 30 will be 75 brought into electrical engagement with each other, thus completing the circuit through the lamp 19.

80 While I have illustrated a construction which I believe to be particularly effective, yet it is obvious that many minor changes might be made, without departing from the spirit of the invention. It will be seen that this signal eliminates the necessity of the driver projecting an arm, in order to indicate his intention of turning the machine out of the straight path and that the driver of the automobile need not remove his hands from the wheel, in order to actuate the signal and need not actuate the signal at all, if 85 for any reason he sees fit not to do so, as in a very crowded street, where the semaphore arm might project too far. Preferably the semaphore target or blade will be stamped out of sheet metal.

95 Having thus described my invention, what I claim is:

1. The combination with an automobile, of a vertically disposed housing mounted on the side wall thereof and having laterally divergent side walls, the lower ends of the side walls being relatively wide, a semaphore arm pivotally mounted in the upper end of the housing, and T-shaped in cross section, a target mounted upon the outer end of the arm and having inwardly convergent side walls to fit within the side walls of the housing, and manually operated means for shifting the arm to a horizontal position.

100 2. The combination with an automobile, of a vertically disposed laterally opening housing mounted on the side wall thereof, a semaphore pivotally connected at its upper end to the housing and movable from a vertically concealed position to a horizontally 105 display position, said semaphore including a hollow target having lenses, an electric light disposed within the target and connected in circuit with a source of electrical energy, and a latch device yieldingly holding the semaphore in a vertical position within the housing and acting to break the circuit to said electric lamp when the semaphore is in a vertical position and close said circuit when the semaphore is in a horizontal 110 position.

115 3. The combination with an automobile, of a vertically disposed laterally opening housing, a semaphore pivotally connected at its outer end to the housing and movable 120

from a vertical concealed position to a horizontal position, the semaphore including a target, and oppositely disposed latching members mounted within the housing at its lower end and resiliently urged toward each other, the target having oppositely disposed recesses in which the latching member is engaged when the target is within the housing.

4. The combination with an automobile, of a vertically disposed laterally opening housing, a semaphore pivotally connected at its outer end to the housing and movable from a vertical concealed position to a horizontal position, the semaphore including a hollow target having lenses and an electric light disposed within the target and connected in an interrupted circuit with a source of electrical energy, oppositely disposed latching members mounted within the housing at its lower end and resiliently urged toward each other, the target having oppositely disposed recesses in which the latching member is engaged when the target is within the housing, a fixed contact connected in said light circuit, and a contact carried by one of said latching members and urged away from the fixed contact when the target is engaged by the latch members but

engaging with the fixed contact when the target is removed from the housing.

5. The combination with an automobile, of a vertically disposed laterally opening housing, a semaphore pivotally connected to the upper end of the housing and movable from a vertical to a horizontal position and vice versa, said semaphore including a hollow target having lenses, and an electric light disposed within the target and connected in an interrupted circuit with a source of electrical energy, said target having inwardly converging side walls, said side walls at the apex of the target being provided with upwardly disposed recesses, a pair of oppositely disposed clamping members having rounded outer ends engageable in said recesses when the target is within the housing, a rod passing through the clamping members, and springs on the rod urging said clamping members toward each other.

In testimony whereof I hereunto affix my signature in the presence of two witnesses.

HARRY GIBNEY CRAFT.
